ATTORNEY

UNITED STATES PATENT OFFICE

OTTO NESTOR BERMAN, OF FOREST HILLS, NEW YORK, ASSIGNOR TO STANDARD DEVICES, INC., A CORPORATION OF DELAWARE

CIGAR LIGHTER

Application filed October 26, 1927. Serial No. 228,746.

My invention relates to cigar lighters of the kind adapted to be carried in the pocket, my more particular purpose being to provide a device of this kind in which the ignition is effected by means of a hand controlled movement of one part of the casing relatively to another part thereof, thus avoiding all necessity for projecting or extending levers, knobs and the like, which are objectionable in many ways.

More particularly stated, my invention comprehends a cigar lighter in which the ignition mechanism is housed within a casing one corner of which is movable relatively to other parts thereof, so that the operator, in using the device to strike a light, practically presses one corner of the casing inwardly, without substantially disturbing the casing or marring the symmetrical form thereof.

20 My invention further contemplates giving the casing and parts carried thereby such form and arrangement as to conserve a certain space within the casing and render the same available for holding a relatively larger volume of liquid hydrocarbon fuel.

My invention further contemplates various details of construction and operation, whereby the general efficiency of the cigar lighter is greatly improved.

30 Reference is made to the accompanying drawing forming a part of this specification, and in which like reference characters indicate like parts throughout the respective figures.

35 Figure 1 is a substantially central vertical section through one form of my improved cigar lighter showing the same with its various movable parts as occupying their respective normal positions, as when the device is carried in the pocket.

40 Figure 2 is a substantially vertical central section through the form of my device appearing in Figure 1, but with the various movable parts occupying the positions they respectively occupy when they are in their abnormal conditions, as when the device is actually being used for striking a light.

45 Figure 3 is a side elevation of my device, 50 shown as partly broken away, and with its

movable parts occupying the positions contemplated for them in Figure 1.

Figure 4 is a section on the line 4—4 of Figure 1, looking in the direction indicated by the arrows.

55 Figure 5 is a section on the line 5—5 of Figure 1, looking in the direction indicated by the arrows.

Figure 6 is a fragmentary side elevation of another form of my device, with its movable parts occupying their respective abnormal positions.

60 A casing body member is shown at 7 and provided at one of its edges with an opening 8, in the form of a notch, as indicated more particularly in Figure 3.

65 The casing is further provided with a partition wall 9, having two portions 10 and 11 extending laterally from it, so as to completely partition off the casing into two parts, as may be understood from Figure 1.

70 The casing is further provided with a boundary wall 12, having a bent portion 13 of the form shown in Figures 1 and 2.

75 By this arrangement there is formed a compartment 14, used as a fuel chamber and having a somewhat irregular form, but which does not completely fill the casing.

80 The casing is further provided with a fuel plug 15, which is removable. The operator by removing the fuel plug 15 can introduce liquid hydrocarbon fuel into the fuel chamber 14, and by replacing the plug can retain the fuel in position, until it is used up.

85 Connected with the portion 11 of the partition wall, and extending through the same, is a tube 16, serving as a flint holder. A flint 17 is housed within this flint holder. This flint is simply a transient member of pyrophoric material, usually a sparking alloy, which is gradually used up and which perishes in the using, in the manner well known in this art.

90 A compression spring 18 engages the flint 17, and presses it constantly to the right according to Figure 1. Engaging the spring 18 is an adjusting screw 19, which is used by the operator for controlling pressure of the spring 18 against the flint. The screw 19

may also be used for removing and replacing the spring and flint.

A wick is shown at 20, and extends through a burner tube 21, into the slot 8. That is, an end portion 22 of the wick protrudes slightly from the burner tube, as may be understood from Figures 1 and 2.

The casing 7 is provided with two end caps, 23 and 24, of different form. The end cap 23 extends entirely across one end of the casing, but the end cap 24 extends only a little more than half way across the opposite end of the casing.

Carried by the casing 7 and movable relatively thereto is a corner piece 25, having a form somewhat similar to that of the end cap 24, these two parts having together such form that, with the various movable parts occupying their respective normal positions as indicated in Figures 1 and 3, the corner piece 25 and the end cap 24 together appear as practically a single end cap; and yet when the corner piece 5 is moved into its abnormal position, as indicated in Figure 2 and as hereinafter more particularly described, such movement does not greatly disturb the general symmetry of the casing as it appears to the eye, except to give the casing the appearance of being sunken inward at one of its corners. This movement of the corner piece 25, under control of the operator's thumb as hereinafter described, is used for actuating the ignition mechanism and thus in striking a light.

In some instances, as shown in Figure 6, the corner piece 25 may be given such construction and may be so formed relatively to other parts as to project slightly from the adjacent end of the casing when the cigar lighter is in such condition that the various movable parts thereof occupy their respective normal positions. By a very slight protrusion 26 of the corner piece 25, with the device in its normal condition the stroke of the corner piece 25 and parts actuated thereby is lengthened a little, so that the ignition mechanism can work effectively. Besides, there is effected a considerable saving of space, without the attendant evil of projecting knobs, arms, levers or the like, which would otherwise be necessary to actuate the ignition mechanism to an equal extent.

Rigidly connected with the corner piece 25, and extending therefrom parallel with each other are a pair of guide pins 27, 27, of the form indicated in Figures 1 and 4. Each of these guide pins is of half-round form, as shown in Figure 4, the casing 7 being slightly concave or dented inwardly at 28, as indicated in Figures 1 and 2, to accommodate the form of the guide pins, as may be understood from Figures 3 and 6. In other words, the portion of the casing immediately adjacent the guide pins 27, 27 are fashioned to serve as bearings for the guide pins, which are

movable in the direction in which they extend.

Housed within the casing 7, and slidable relative thereto, is a barrel 29, provided with a central opening 30. Engaging this barrel is a spiral spring 31, one end of which rests against the end cap 23. The spring 31 by its pressure tends to force the barrel 29 to the left according to the Figures 1, 2 and 3.

The guide pins 27, 27 extend slidably through the portion 11 of the partition wall, and are secured rigidly to the barrel 29. Thus by means of the guide pins 27, 27, motion may be transmitted from the corner piece 25 to the barrel 29.

The barrel 29 carries a rack bar 32, and the teeth of this rack bar mesh with the teeth of a gear wheel 33. The gear wheel 33 and a flint wheel 34 are loosely mounted upon a shaft 35, which extends directly through the casing. A spring washer 36 encircles the shaft 35, and presses the flint wheel constantly against the gear wheel. The gear wheel has a to-and-fro rocking movement, and the friction wheel 34 has a step by step movement always in a single direction, as is usual in this art.

My device has two general conditions, namely its normal condition of inactivity, indicated in Figures 1 and 3, and its abnormal condition of activity, indicated in Figure 2. When the device is in its normal condition, it is usually carried in the pocket. When in its abnormal condition it is used for lighting cigars or cigarettes, or at least for striking a light of some kind, and for this purpose may be held in and be operated by one hand. The flame is shown at 36a.

Suppose, now, that my cigar lighter is in its normal condition of inactivity, as indicated in Figure 1, and that the operator wishes to use it, in order to strike a light. He simply removes the cigar lighter from his pocket with one hand, and continuing to hold it in that hand, he places his thumb against the corner piece 25, moving the latter to the right according to Figure 1. In doing this he causes the barrel 29 to move to the right, thus uncovering the end portion 22 of the wick. The movement of the barrel 29 causes the rack bar 32 to turn the gear wheel 33, thus operating the friction wheel 34 against the flint 17. This causes sparks to be thrown upwardly. These sparks pass between the guide pins 27, 27 and ignite the end portion 22 of the wick, causing the flame 36a to make its appearance, as indicated in Figure 2. The lighting operation being accomplished the operator now relaxes the pressure of the thumb. Thereupon the barrel 29, under pressure of the spring 31, is moved to the left according to Figures 1 and 3, these and other movable parts thus being brought back to their respective normal positions.

I do not limit myself to the precise mecha-

nism shown, as variations may be made therein without departing from my invention, the scope of which is commensurate with my claims.

Having thus described my invention, what I claim as new and desire to secure by Letters Patent is as follows:—

1. A cigar lighter, comprising a casing provided with an opening, a barrel slidably mounted within said casing for the purpose of closing said opening, mechanism connected with said barrel for striking a light, a corner piece carried by said casing and movable relatively thereto, and connections from said corner piece to said barrel for enabling said barrel to be actuated by movements of said corner piece. 70
2. A cigar lighter, comprising a casing having three corners which are rigid relative to each other, said casing being provided with an opening, a sliding member housed within said casing and movable relative thereto for the purpose of closing said door, a corner piece carried by said casing and movable relatively thereto by the operator's thumb, ignition mechanism mounted within said casing and disposed adjacent said opening, and a pair of bars connected with said corner piece and extending therefrom to said sliding member, for enabling said sliding member to be actuated by movements of said corner piece. 75
3. A cigar lighter, comprising a casing having three corners which are rigid relative to each other, said casing also being provided with an opening, a sliding member housed within said casing and movable relative thereto for the purpose of closing said opening, a corner piece carried by said casing and movable relatively thereto by the operator's thumb, a pair of bars connected with said corner piece and with said sliding member for enabling movements of said corner piece to actuate said sliding member, and ignition mechanism mounted within said casing and disposed adjacent said opening, said ignition mechanism being connected with said bars and actuated by movements thereof, and so located relatively to said opening and to said bars that said bars do not obstruct the passage from said ignition mechanism to said opening. 80
4. A cigar lighter, comprising a flat hollow casing provided with three corners which are rigid relative to each other, said casing being further provided with an opening, a closure member slidably mounted within said casing for the purpose of closing said opening, a corner piece carried by said casing and movable relatively thereto, ignition mechanism housed within said casing and disposed adjacent said opening for the purpose of striking a light, and connections from said corner piece to said closure member and to said ignition mechanism for enabling move- 85
5. A cigar lighter, comprising a casing having three corners which are rigid relative to each other, said casing being provided with an opening, a sliding member housed within said casing and movable relative thereto for the purpose of closing said door, a corner piece carried by said casing and movable relatively thereto by the operator's thumb, ignition mechanism mounted within said casing and disposed adjacent said opening, and a pair of bars connected with said corner piece and extending therefrom to said sliding member, for enabling said sliding member to be actuated by movements of said corner piece. 90
6. A cigar lighter, comprising a casing having three corners which are rigid relative to each other, said casing also being provided with an opening, a sliding member housed within said casing and movable relative thereto for the purpose of closing said opening, a corner piece carried by said casing and movable relatively thereto by the operator's thumb, a pair of bars connected with said corner piece and with said sliding member for enabling movements of said corner piece to actuate said sliding member, and ignition mechanism mounted within said casing and disposed adjacent said opening, said ignition mechanism being connected with said bars and actuated by movements thereof, and so located relatively to said opening and to said bars that said bars do not obstruct the passage from said ignition mechanism to said opening. 95
7. A cigar lighter, comprising a flat hollow casing provided with three corners which are rigid relative to each other, said casing being further provided with an opening, a closure member slidably mounted within said casing for the purpose of closing said opening, a corner piece carried by said casing and movable relatively thereto, ignition mechanism housed within said casing and disposed adjacent said opening for the purpose of striking a light, and connections from said corner piece to said closure member and to said ignition mechanism for enabling move- 100
8. A cigar lighter, comprising a casing having three corners which are rigid relative to each other, said casing being provided with an opening, a sliding member housed within said casing and movable relative thereto for the purpose of closing said door, a corner piece carried by said casing and movable relatively thereto by the operator's thumb, ignition mechanism mounted within said casing and disposed adjacent said opening, and a pair of bars connected with said corner piece and extending therefrom to said sliding member, for enabling said sliding member to be actuated by movements of said corner piece. 105
9. A cigar lighter, comprising a casing having three corners which are rigid relative to each other, said casing also being provided with an opening, a sliding member housed within said casing and movable relative thereto for the purpose of closing said opening, a corner piece carried by said casing and movable relatively thereto by the operator's thumb, a pair of bars connected with said corner piece and with said sliding member for enabling movements of said corner piece to actuate said sliding member, and ignition mechanism mounted within said casing and disposed adjacent said opening, said ignition mechanism being connected with said bars and actuated by movements thereof, and so located relatively to said opening and to said bars that said bars do not obstruct the passage from said ignition mechanism to said opening. 110
10. A cigar lighter, comprising a flat hollow casing provided with three corners which are rigid relative to each other, said casing being further provided with an opening, a closure member slidably mounted within said casing for the purpose of closing said opening, a corner piece carried by said casing and movable relatively thereto, ignition mechanism housed within said casing and disposed adjacent said opening for the purpose of striking a light, and connections from said corner piece to said closure member and to said ignition mechanism for enabling move- 115
11. A cigar lighter, comprising a casing having three corners which are rigid relative to each other, said casing being provided with an opening, a sliding member housed within said casing and movable relative thereto for the purpose of closing said door, a corner piece carried by said casing and movable relatively thereto by the operator's thumb, ignition mechanism mounted within said casing and disposed adjacent said opening, and a pair of bars connected with said corner piece and extending therefrom to said sliding member, for enabling said sliding member to be actuated by movements of said corner piece. 120
12. A cigar lighter, comprising a flat hollow casing provided with three corners which are rigid relative to each other, said casing being further provided with an opening, a closure member slidably mounted within said casing for the purpose of closing said opening, a corner piece carried by said casing and movable relatively thereto, ignition mechanism housed within said casing and disposed adjacent said opening for the purpose of striking a light, and connections from said corner piece to said closure member and to said ignition mechanism for enabling move- 125
13. A cigar lighter, comprising a casing having three corners which are rigid relative to each other, said casing also being provided with an opening, a sliding member housed within said casing and movable relative thereto for the purpose of closing said opening, a corner piece carried by said casing and movable relatively thereto by the operator's thumb, ignition mechanism mounted within said casing and disposed adjacent said opening, and a pair of bars connected with said corner piece and extending therefrom to said sliding member, for enabling said sliding member to be actuated by movements of said corner piece. 130

ments of said corner piece to actuate said closure member and said ignition mechanism.

Signed at New York city, in the county of New York and State of New York, this 14th day of October, 1927.

OTTO NESTOR BERMAN.
